DESIGN FOR A SHOE RACK

Samuel George Arch, Outremont, Quebec,
Canada

Application April 7, 1938, Serial No. 76,347

Term of patent 7 years

To all whom it may concern:

Be it known that I, Samuel George Arch, a subject of the King of Great Britain, residing at 760a De L'Epee Avenue, in the city of Outremont, in the Province of Quebec, in the Dominion of Canada, have invented a new, original, and ornamental Design for a Shoe Rack, of which the following is a specification, reference being had to the accompanying drawing, forming part thereof.

The figure is a perspective view of the shoe rack showing my design.

I claim:

The ornamental design for a shoe rack, as shown.

SAMUEL GEORGE ARCH.
